UNITED STATES PATENT OFFICE.

ALBERT T. WEISS, OF ROCHESTER, NEW YORK, ASSIGNOR TO YAWMAN & ERBE MANUFACTURING COMPANY, OF ROCHESTER, NEW YORK, A CORPORATION OF NEW YORK.

METALLIC-FURNITURE DRAWER.

1,136,071.

Specification of Letters Patent. Patented Apr. 20, 1915.

Application filed December 18, 1913. Serial No. 807,488.

To all whom it may concern:

Be it known that I, ALBERT T. WEISS, of Rochester, in the county of Monroe and State of New York, have invented certain new and useful Improvements in Metallic-Furniture Drawers; and I do hereby declare the following to be a full, clear, and exact description of the same, reference being had to the accompanying drawings forming a part of this specification and to the reference numerals marked thereon.

My present invention relates to furniture and more particularly to metallic furniture of the kind used in office and library for the filing of papers and documents and the invention has for its object to provide a simple, neat and efficient drawer that can be conveniently and cheaply constructed of sheet metal, being strongly constructed and yet capable of being easily and quickly assembled.

To these and other ends the invention consists in certain improvements and combinations of parts, all as will be hereinafter more fully described, the novel features being pointed out in the claims at the end of the specification.

In the drawings: Figure 1 is a perspective view of a drawer constructed in accordance with and illustrating one embodiment of my invention, the view being taken from the rear; Fig. 2 is a vertical central section through the front thereof; Fig. 3 is a horizontal section through the front taken substantially on the line 3—3 of Fig. 2; Fig. 4 is a similar view on the line 4—4 of Fig. 2; Fig. 5 is a fragmentary perspective view of the front end of the piece forming the bottom and side walls of the drawer, and Fig. 6 is a fragmentary perspective view of the lower portion of the front plate with which the part shown in Fig. 5 coöperates.

Similar reference numerals throughout the several figures indicate the same parts.

Certain features of my invention are chiefly useful in connection with filing receptacles familiarly known as "document drawers", and such a drawer has been illustrated herein to comprise a front wall indicated generally at 1, low side walls 2, a bottom wall 3 and side rails 4 above the side walls and located about midway of the height of the front wall.

The front wall 1 comprises a front plate 5, the margins of which are turned rear-

wardly all around at 6 and thence bent inwardly at 7 to constitute flanges parallel to and spaced from the body of the plate. Disposed against the inner side of the front plate is a lining plate 8 having forwardly turned flanges 9 at its sides and bottom acting as spacing means engaging the front plate. These flanges are preferably slightly larger or deeper than the rearwardly turned portion 6 of the front plate so that they abut flatwise against the edges of the flanges 7 making a neat and smooth joint. At the upper edge of the lining plate the two plates are interlocked by an upwardly turned flange 10 on the lining plate that engages beneath the corresponding flange 7 on the front plate and acts additionally to the securing devices hereinafter mentioned to prevent separation of the plates at this point during the strains incident to supporting the weight of the drawer and its contents from the front wall thereof. The two plates are secured together by bolts or equivalent devices 11 which extend through the front plate and through forwardly embossed areas 12 and 13 on the lining plate that protect the inner ends of the bolts against contact with the contents of the drawer and also act as spacing and stiffening means in addition to the flanges 6. The bolts are preferably also utilized for attaching a handle 14 on the outside of the front plate and of the front drawer wall as a whole.

The bottom and side walls 3 and 2 respectively, are preferably formed in one of a single piece of sheet material. At its forward end the bottom wall is provided with a downwardly turned flange 15 that interlocks with and forwardly of the bottom flange 7 on the front plate 5, while the forward ends of the side walls 2 are somewhat similarly fitted with outwardly or laterally turned flanges 16 interlocking with the inwardly turned flanges 7 at the sides of the front plate, which flanges are cut away slightly at this point, as indicated at 17. This cut away portion prevents the side walls from slipping upwardly. The lining plate 8 abuts all of these walls on the inside and prevents disengagement of the described groups of flanges, as is apparent from the figures, so that as long as this plate is in place it maintains the relationship of the front wall 1 with the body of the drawer.

The side rails 4 may be constituted of a single strip of material, as clearly indicated in Fig. 1. Their forward ends enter notches 18 in the flanges 7 that hold them against upward or downward movement and thence proceed inwardly at 19 to the center of the front wall where they are pierced by the bolts 11 and thus clamped between the front plate 5 and the lining plate 8. To compensate for this added thickness, a block 20 of the same size may be inserted between the plates in the region of the boss 13, as shown in Figs. 2 and 4.

It will be noted that the lining plate 8 is in the nature of a keystone part that holds the other parts in proper coöperation while it is itself connected in a simple manner by the same securing devices that are used to attach the handle 14. Assembling is thereby greatly facilitated. The hollow nature of the front wall 1 produces an air space that is useful as fire protection while at the same time the spacing of the plates 5 and 8 contributes a more substantial appearance and lends itself better to the purposes in hand.

when a finish in imitation of wood is desired in the cabinet and drawers.

I claim as my invention:

1. In a drawer, the combination with a front plate, and a lining plate disposed against the inner side thereof, of side rails for the drawer relatively heavier material having their forward ends turned inwardly to extend across the face of the front plate and secured between the latter and the lining plate.

2. In a drawer, the combination with a front plate, a lining plate disposed against the inner side thereof and a handle on the outside of the front plate, of side rails for the drawer having their forward ends turned inwardly between the front plate and the lining plate and securing devices for the handle extending through the front and lining plates to hold them together and also acting as securing means for the side rails.

ALBERT T. WEISS.
